UNITED STATES PATENT OFFICE

EARL THOMAS FLOYD, OF NEAR TEMPLE, PENNSYLVANIA, ASSIGNOR TO THE NOLDE AND HORST COMPANY, OF READING, PENNSYLVANIA, A CORPORATION OF PENNSYLVANIA

STRIPED STOCKING

Application filed June 19, 1928. Serial No. 286,679.

This invention relates to knitted stockings having longitudinal striping; and it provides for producing improved ornamental effects by employing in connection with 5 contrasting body yarns knitted in alternating courses, separate striping yarn interknitted with one or other of said body yarns in determined wales only, with unknitted portions thereof at the rear floated diagonally 10 across intervening courses of the other body yarn, as fully set forth in connection with the accompanying drawing and clearly defined in the subjoined claim.

Fig. 1 is an outline view of a stocking with 15 a fragmentary diagrammatic showing thereon to indicate the improved ornamentation which my invention provides for; the novel construction thereof being clearly revealed by the enlarged showing thereof in Fig. 2. 20 Fig. 3 diagrammatically indicates a two-feed cam arrangement for producing the alternating courses of different yarns in the knitting of the stocking body.

The stocking body indicated is knitted of 25 two different yarns *b* and *c*, shown in enlarged Fig. 2 as of different coloring; these being knitted simultaneously in alternating courses, by the action of two sets of knitting cams as indicated in Fig. 3, so the whole body 30 is made up of closely parallel contrasting courses.

In the diagrammatic double-feed knitting-cam showing of Fig. 3, arrows *b'* and *c'* indicate the respective body yarn feeds to corresponding needles which are not shown. The stripe effects such as indicated in Fig. 1, 35 are produced by simultaneously feeding a plating yarn *d* to certain of the needles, as determined by the width of the stripe to be 40 produced and the desired color effect, arrow *d'* indicating the feed of said plating yarn.

This additional yarn is fed for instance, 45 as indicated in the drawings, to needles which are knitting the lighter body yarn, so as to be formed into loops with the latter in determined wales of the course and produce a different color effect in said wales from that produced by said lighter colored body yarn in the main portion of the course; the portions 50 of this additional plating yarn which

are not so interknitted being floated at the rear of the fabric, in diagonal lines crossing the intervening course of different body yarn as shown in Fig. 2.

If the additional yarn thus platingly interknitted with this body yarn is made to correspond with the other body yarn of the adjacent courses, a solid stripe effect is produced without showing of the lighter colored body yarn therein; if this additional yarn differs in coloring from both of the body yarns a radically different stripe effect is produced; and if the additional yarn is fed with and interknitted with the other body yarn instead, 55 a still different effect is produced; so that a great variety of designs may be readily produced by required variations in the relative character of the additional plating yarn employed, by its interknitting with one or other 60 of the different body yarns employed in the alternate courses, and by variation in the number of wales in which the plating thread is made to appear; the hidden floating portions of the latter in all cases diagonally 65 crossing an intervening course.

What I claim is:—

A stocking knit with two different body 70 yarns simultaneously fed in alternating courses, and having separate striping yarn plaitedly interknitted in each wale with one 75 of said body yarns to appear on the surface in the alternate courses of determined wales and with each rear portion of said striping yarn floated diagonally across an intervening 80 course of the other body yarn to appear only 85 on the reverse side of the stocking.

In testimony whereof I affix my signature,
EARL T. FLOYD.
